SOUND TRANSLATING DEVICE

Harold Charles Pye, Oak Park, Ill., assignor to
Associated Electric Laboratories, Inc., Chicago,
Ill., a corporation of Delaware

Application May 24, 1938, Serial No. 209,805

1 Claim. (Cl. 175—336)

The present invention relates to sound translating devices and more particularly to a winding spool and armature assembly for a sound translating device of the magnetic or sound powered type.

In a telephone transmitter of this type, a magnetic field structure is provided which conventionally comprises a permanent magnet and two sets of adjacent pole pieces, the adjacent pole pieces of each set being of opposite polarity. A pivotally mounted magnetic armature is associated with the magnetic field structure, the opposite ends of the armature being disposed between the pole pieces of the respective sets. A sound wave responsive diaphragm is connected and arranged to subject the ends of the armature to vibratory movements between the pole pieces of the respective sets and corresponding to the sound to be transmitted. A winding or voice coil carried by a winding spool is electro-magnetically coupled to the armature, whereby an electromotive force is generated in the winding corresponding to the vibratory movements of the armature with respect to the adjacent pole pieces of the two sets, in a known manner. In prior telephone transmitters of this type, the vibratory armature is pivotally mounted on brackets or the like carried by the field structure or by an external supporting member. While armature mountings of this character are reasonably satisfactory, they are expensive to manufacture and require delicate adjustments in order properly to align the armature with respect to the sets of adjacent pole pieces of the field structure.

Accordingly, it is an object of the present invention to provide an improved sound translating device of the type described having embodied therein a winding spool and armature assembly in which the armature is pivotally mounted on the winding spool and requires no external support.

Another object of the invention is to provide a telephone transmitter of the type described including an improved armature mounting member which is so constructed and arranged that the member is subjected to torsional strains when the armature is moved, whereby the movement of the armature is directly proportional to the operating force exerted thereon.

A further object of the invention is to provide an improved winding spool and armature assembly which is of extremely simple and rugged construction, and which is compact and economical to manufacture.

In general, the objects as set forth above are attained in accordance with the present invention by providing an assembly of the character noted comprising a winding spool provided with a hollow body carrying spaced apart winding retaining heads, and an armature arranged within the hollow body and supported by the wall of the body for vibratory movements out of contact with the wall of the body of the winding spool. More specifically, the winding spool is formed of insulating material, while the armature is formed of flat magnetic stock and provided with two transversely extending integral lugs, each of which is provided with a length of reduced cross-sectional area. The lugs on the armature are rigidly supported in recesses formed in the wall of the body of the winding spool, whereby the armature is mounted for vibratory movements about an axis extending transversely of the winding spool and out of contact with the wall of the body of the winding spool; and the lengths of reduced cross-sectional area of the lugs on the armature are subjected to localized torsional strains, when the armature is moved.

The novel features believed to be characteristic of the invention are set forth the particularity in the appended claims. The invention, both as to its organization and method of operation, together with further objects and advantages thereof, will best be understood by reference to the following specification taken in connection with the accompanying drawing, in which Figure 1 is a perspective view, partly broken away, of the winding spool and armature assembly embodying the present invention; Fig. 2 is a plan view, partly broken away, of the assembly shown in Fig. 1; Fig. 3 is a sectional view of the assembly, taken along the line 3—3 in Fig. 2; and Fig. 4 is a side elevational view, partly in section, of a telephone transmitter of the magnetic or sound powered type provided with a winding spool and armature assembly constructed in accordance with the present invention.

Referring now more particularly to Fig. 4 of the drawing, there is illustrated a sound translating device in the form of a telephone transmitter of the magnetic or sound powered type embodying a winding spool and armature assembly constructed in accordance with the present invention and comprising a field structure 10 and a winding spool and armature assembly 11. The field structure 10 includes a permanent magnet 12 and two field members 13 and 14 rigidly secured to the opposite ends thereof, the field member 13 being secured to the north pole of

the permanent magnet 12, and the field member 14 being secured to the south pole of the permanent magnet 12. The field members 13 and 14 are each provided with two pole pieces 15, 16 and 17, 18, respectively, the pole pieces 15 and 17 being arranged in spaced apart relation adjacent each other and constituting a set, and the pole pieces 16 and 18 being arranged in a similar manner and constituting a set.

The assembly 11 comprises a winding spool 19 provided with a body 19^a, carrying two spaced apart winding retaining heads 19^b, and a winding 20 arranged about the body 19^a between the retaining heads 19^b. An armature 21 is pivotally mounted on the winding spool 19 in a manner more fully described subsequently and is supported by the winding spool 19 between the two sets of pole pieces, one end 21^a of the armature 21 being disposed between the oppositely disposed pole faces of the set of adjacent pole pieces 15 and 17 and the other end 21^b of the armature 21 being disposed between the oppositely disposed pole faces of the set of adjacent pole pieces 16 and 18. The armature 21 is arranged within a longitudinally extending opening provided in the winding spool 19, and the ends 21^a and 21^b thereof are adapted to vibrate between the associated sets of adjacent pole pieces 15, 17 and 16, 18, respectively, and out of contact with the wall of the body of the winding spool 19. The end 21^a of the armature 21 is provided with a projecting operating lug 22 having an opening therein in which one end of a rod 23 is secured, the rod 23 extending through an opening 13^a formed in the field member 13, and the other end thereof being secured to a sound wave responsive diaphragm 24 supported about its periphery by suitable clamping means 25. Normally, the armature 21 occupies a position wherein the opposite ends thereof are disposed intermediate the adjacent pole pieces of the two sets and is adapted to be vibrated by the rod 23 when the diaphragm 24 is vibrated by sound waves impinging thereon. Thus, the movement of the armature 21 is controlled in accordance with the vibratory movements of the diaphragm 24, the vibratory movements of the diaphragm 24 corresponding to the vibrations of the air produced by the sound to be transmitted. As the armature 21 is moved in a clockwise direction about its pivot, the magnetic field of the field structure 10 traverses a path extending from the north pole of the permanent magnet 12 by way of the field member 13, the pole piece 16, the armature 21, the pole piece 17, and the field member 14 to the south pole of the permanent magnet 12. On the other hand, when the armature is moved in a counterclockwise direction about its pivot, the magnetic field of the field structure 10 traverses a path extending from the north pole of the permanent magnet 12 by way of the field member 13, the pole piece 18, the armature 21, the pole piece 18, and the field member 14 to the south pole of the permanent magnet 12. Thus, during the vibratory movements of the armature 21, the magnetic field of the field structure 10 traverses the armature 21 in opposite directions, causing a corresponding electromotive force to be generated in the winding 20 electromagnetically coupled thereto. The electromotive force generated in the winding 20 is transmitted to a distant point where it is utilized in a suitable receiver or other translating device to reproduce the sound transmitted in a well known manner.

The winding spool and armature assembly 11A

75 illustrated in Figs. 1, 2 and 3 comprises a winding spool 30 formed of insulating material such as "Bakelite" and an armature 31 formed of flat magnetic stock. The winding spool 30 comprises a body 32 carrying two spaced apart winding retaining heads 33, the body 32 of the winding spool 30 including top and bottom members 34 and 35, respectively, secured in spaced apart relation to two side members 36. The top and bottom members 34 and 35 extend between the winding retaining heads 33 and are preferably formed integral therewith; while the side members 36 extend between the winding retaining heads 33, being arranged in aligned openings 33^a formed in the winding retaining heads 33. The armature 31 is provided with a longitudinally extending operating lug 31^a and two transversely extending spaced apart lugs 37 intermediate the ends thereof. Each of the lugs 37 projects from one side of the armature 31 and is provided with a head 37^a connected by a length 37^b to the armature 31, the length 37^b being of reduced cross-sectional area. Each of the side members 36 of the body 32 of the winding spool 30 is provided with a recess 36^a therein, which is adapted to receive the head 37^a of one of the lugs 37.

In constructing the assembly 11A, the heads 37^a of the lugs 37 on the armature 31 are inserted into the recesses 36^a in the side members 36 and securely retained in place therein by an adhesive or the like. The assembled armature 31 and side members 36 are then inserted through the openings 33^a provided in the winding retaining heads 33 and securely retained in place by an adhesive or the like.

The opposite ends of the armature 31 project through the openings formed in the winding retaining heads 33 and are protected against injury by projections 38 provided on the ends of the side members 36. The upper and lower members 34 and 35, respectively, of the body 32 are spaced a short distance from the upper and lower surfaces of the armature 31, and the side members 36 are spaced a short distance from the side surfaces of the armature 31 by the lengths 37^b of the lugs 37. Thus, the body 32 of the winding spool 30 is hollow, the upper and lower members 34 and 35, respectively, and the side members 36 constituting a wall surrounding a narrow opening extending longitudinally therethrough; and the armature 31 is arranged within the opening in the body 32. The armature 31 is supported by the lugs 37 for vibratory movements out of contact with the wall of the body 32 and about an axis extending between the lugs 37 transversely of the winding spool 30. When the armature 31 is moved from its normal position, the lugs 37 are subjected to torsional strains, the strains being localized in the lengths of reduced cross-sectional area 37^b of the lugs 37. This torsional mounting of the armature 31 is very advantageous, as it causes the armature 31 to be deflected an amount precisely corresponding to the force exerted upon the operating lug 31^a, the deflection of the armature 31 being directly proportional to the force exerted upon the operating lug 31^a over a wide range.

From the foregoing description it is apparent that a unitary winding spool and armature assembly for a telephone transmitter is provided, which is of rugged construction and comprises a minimum number of parts. Moreover, the assembly is compact and the pivotally mounted armature therein requires no external support. While the features of the present invention have

been illustrated as being embodied in a telephone transmitter, it is apparent that they may be readily embodied in a telephone receiver or other sound translating device.

While there has been described what is at present considered to be the preferred embodiment of the invention, it will be understood that various modifications may be made therein, and it is contemplated to cover in the appended claim all such modifications as fall within the true spirit and scope of the present invention.

What is claimed is:

An assembly for a sound translating device comprising, in combination, a winding spool formed of insulating material and including a longitudinally extending body and laterally extending winding-retaining heads carried on the opposite ends of said body, said body including

5 top and bottom walls formed integral with said winding-retaining heads and side walls arranged in aligned openings provided in said winding-retaining heads, the walls of said body being arranged to define a narrow opening extending longitudinally through said body, and an armature formed of flat magnetic stock and provided with 10 two transversely extending integral lugs, said armature being arranged in the opening in said body and the ends of said lugs being rigidly supported in aligned openings provided in the side walls of said body, whereby said armature is mounted for vibratory movements about an axis extending transversely of said winding spool and out of contact with the walls of said body and said lugs are subjected to torsional strains when said armature is moved.
